UNITED STATES PATENT OFFICE.

FRANK A. PHILLIPPI, OF POTTSTOWN, PENNSYLVANIA, ASSIGNOR OF ONE-HALF TO
J. ROY KINCKINER, OF POTTSTOWN, PENNSYLVANIA.

WATER-COOLER.

1,391,075.

Specification of Letters Patent. Patented Sept. 20, 1921.

Application filed December 3, 1919. Serial No. 342,216.

To all whom it may concern:

Be it known that I, FRANK A. PHILLIPPI, a citizen of the United States, and a resident of Pottstown, in the county of Montgomery and State of Pennsylvania, have invented 5 certain new and useful Improvements in Water-Coolers, of which the following is a specification.

This invention has for its main object to 10 provide a sanitary cooler for liquids, capable of continuous or intermittent service for an unlimited period of time, all of the parts in contact with liquids being finished with a vitreous enamel or made of porcelain.

15 A further object is to provide means whereby the interior is readily accessible for cleansing.

A still further object is to provide a cooler 20 comprised of few and simple parts relatively inexpensive to manufacture, and which is highly economical in the use of a refrigerant.

These and other like objects are attained 25 by the novel construction and combination of parts and principles hereinafter described, and shown in the accompanying drawings, forming a material part of this disclosure, and in which—

Figure 1 is a vertical sectional view taken 30 through a cooler made in accordance with the invention,

Fig. 2 is a transverse sectional view taken on line 2—2 of Fig. 1.

Fig. 3 is a similar transverse sectional view taken on line 3—3 of Fig. 1.

35 Fig. 4 is a top plan view showing a pair of cooler units in their casing.

Fig. 5 is an enlarged fragmentary sectional view taken on line 5—5 of Fig. 4.

Fig. 6 is a perspective view showing one of 40 the plates used in one form of the cooler units.

Referring to the drawings in detail, the 45 numeral 10 indicates the bottom of a box or cabinet having side and end walls respectively 11 and 12, and provided with a removable cover 13, as best shown in Figs. 1 and 4.

The interior of the cabinet is provided 50 with a water-tight lining, as sheet copper, extending over the side and bottom walls, the

same being adapted to contain ice 14 or other refrigerant, and provided with a suitable overflow (not shown) for the melted ice.

This cabinet may be made of any desired size so as to contain one or more of the 55 cooler units, each consisting of a cylindrical tank 15, formed with an integral bottom 16, from which projects three or more supporting feet 17 adapted to rest upon the bottom 10, while rising centrally from the bottom 16, 60 of the tank, is a hub 18, containing a screw threaded opening 19, from which leads a passage 20, extending at a right angle to the tank in the radial rib 21, below the bottom and provided with a tight fitting cap 22, at 65 its outer end having a flattened knob 23 by which it may be operated.

Formed integrally with the tank 15, and extending radially inwardly from top to bottom are a plurality of partial partition 70 plates 24, their inner vertical edges containing longitudinal V shaped grooves 25.

The upper end of the tank is beveled or chamfered at its inner edge 26, while circumjacent of the tank, at a point near its 75 upper end, is an integral ring 27, having an overhanging flanged edge 28, and containing a plurality of recesses 29, adapted to position and prevent from turning the beveled, key-like extensions 30, formed with angular arms 80 31, at the lower end of the bolts 32, their screw-threaded portions 33 being engageable by the wing nuts 34, the bolts passing through openings formed within ears 35 extending out from the periphery of the cover plate 36, 85 the openings 37 through which the bolt stems 32 pass being beveled outwardly so that upon loosening the nuts the bolts can be maneuvered to clear the projections 30 from the overhanging edge in an expeditious manner.

The lower, central surface 38 of the cover plate 36 is beveled upon its exterior, complementary to the bevel 26 at the top of the casing, and in order to form a water-tight 95 joint a packing ring 39 is interposed, which upon the bolts being drawn tight, prevents liquid from passing the joint between the cover and tank body.

Centrally of the cover 36 is a threaded 100

opening 40, receptive of a plug 41, having an extending head 32 by which it may be maneuvered, while raised from the upper surface of the cover 36 are a pair of projections 5 43, screw-threaded to receive elbows or like fittings 44, providing for the outlet and inlet of water to the cooler tank by pipes 45 and 46 respectively.

Extending below one of the projections 43 10 is an opening 47, and screw-threaded into its lower end is a tube 53 having at its lower end a spray head consisting of a central tube 48 containing a plurality of small openings 49, circumjacent to which is an annular hood 15 50 directing the effluent from the openings 49 downwardly, causing the streams to strike upon the upturned edge 51, of a disk 52, secured at the lower end of the spray head.

Another head, alike in all respects extends 20 downward from a similar opening below the opposite disposed projection 43, thereby causing the liquid to enter the tube 53 from the bottom of the tank and be discharged from a point near the top through the pipe 25 45 with which the tube 53 communicates.

Arranged to extend vertically in the tank, are a pair of plates 55 and 56, the same having angular side edges 57 adapted to be received within the grooves 25, at the inner 30 edge of the partial partitions 24, each of the plates containing central slots 58 matching with the mating plate, so that when placed together they form four outstanding elements which, in connection with the elements 35 24, form perforate partitions.

In each of the plates 55 and 56 are a plurality of conical openings 59 adapted to cause circulation of the liquid from one compartment to another in the direction indicated by the conical openings, so that liquid having been entered from the lower spray head into one of the compartments is distributed to the others.

In the modification shown at the right of 45 Fig. 1 and in Fig. 3, in place of the plates 55 and 56 there is used a hollow porcelain diffuser comprised of rings 60, formed integrally with the necked portions 61, the rings being of a diameter receivable between 50 the opposed pairs of the partial partition plates 24, and provided at their upper ends with heads 62, held in position by the end 63 of the screw 42, the lower end of the porcelain center resting upon the top of the hub 55 18, the arrangement being such that the liquid is caused to move outwardly as it rises, so as to make contact with the walls of the casing as it is advanced gradually from the bottom to the top of the cooler 60 units.

Particular stress is laid upon the fact that all of the metal parts coming in contact with the liquid to be cooled, are coated with a white, vitreous enamel, rendering all parts 65 smooth, lustrous, and easily cleansed, form-

ing in effect a highly sanitary cooler which has been found in practice to be unusually economical in the use of ice in the surrounding cabinet, and the construction is such that there is nothing to rust, wear or require attention other than filling the cabinet at necessary intervals with cracked ice as indicated. 70

It is further to be understood that the device may be used in combination with a filter 75 and when so used it is preferable to first run the liquid to be cooled through the filter, then into the tank containing the porcelain core, and then through the plate compartment cooler tank to the faucet, bubbler or 80 other issuing point as desired.

The disclosure is to be regarded as descriptive only and not as restrictive or limitative of the invention, of which obviously an embodiment may be constructed including 85 many minor modifications without departing from the general scope herein indicated and hereinafter claimed.

Having thus described my invention and set forth the manner of its construction, application and use, what I claim as new and desire to secure by Letters Patent, is—

1. A cooler comprising a cylindrical tank, a plurality of integrally formed partial partitions extending radially inward from the wall of said tank, means in said tank for causing circulation of water therein, a cover, means for clamping said cover to said tank, an inlet pipe, a spray head engaged therewith, said spray head extending downward within said tank, an outlet pipe, and a cabinet adapted to contain said tank, said cabinet being also adapted to contain ice packed around said tank. 95

2. A cooler comprising a cylindrical tank, 105 a plurality of integrally formed partial partitions extending radially inward from the wall thereof, removable plate partitions extending between said fixed partitions throughout the length of said tank, said removable partitions containing a plurality of conical openings adapted to cause liquid to circulate, a cover having a convex portion suited to fit the upper edge of said tank, a ring having undercut portions extending adjacent to said tank near its upper end, bolts having offset ends engageable below said ring, said bolts passing through extensions formed with said cover, and means for clamping said bolts in position. 110

3. A cooler comprising a cylindrical tank, a plurality of partial partitions extending radially inward from the wall of said tank, said partitions having longitudinal grooves in their inner edges, a cover removably engaged on the tank, a pair of plates mounted to interengage at right angles fitted to slidably engage in said grooves, said plates having a plurality of conical openings arranged in different planes the angle of all of said 125 130

- openings being in the same direction, means in from the walls thereof, a cover for said tank, an inlet and outlet for said tank, and diffusing means extending longitudinally of 10 said tank the full length thereof.
- 5 for cooling said tank by a refrigerant.
4. A cooler comprising a cylindrical tank, longitudinal partitions extending partially

In testimony whereof I have signed my name to this specification.

FRANK A. PHILLIPPI.
